(57) **CLAIM**

The ornamental design for a wheel for an automobile, as shown and described.

DESCRIPTION

FIG. 1 is a front perspective view of a wheel for an automobile in accordance with my new design.

FIG. 2 is a front view thereof.

FIG. 3 is an enlarged view of a portion indicated with numeric 3 in FIG. 1; and,

FIG. 4 is an enlarged view of a portion indicated with numeric 4 in FIG. 1.

The evenly dashed broken lines in the drawings illustrate portions of the wheel for an automobile in which the design is embodied that form no part of the claimed design. The dot-dash lines define the bounds of the design and enlarged views and form no part of the claimed design.
